(57) **CLAIM**

The ornamental design for a display screen with animated graphical user interface, as shown and described.

DESCRIPTION

FIG. 1 is a front view of a first image in a sequence for a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is another view of FIG. 1 with additional broken line subject matter;

FIG. 6 is another view of FIG. 2 with additional broken line subject matter;

FIG. 7 is another view of FIG. 3 with additional broken line subject matter; and,

FIG. 8 is another view of FIG. 4 with additional broken line subject matter.

The appearance of the animated graphical user interface sequentially transitions between the images shown in FIGS. 1-4 and between the images shown in FIGS. 5-8. The process or period in which one image transitions to another image forms no part of the claimed design.

The broken lines in the figures illustrate a computer and portions of the display screen with animated graphical user interface that form no part of the claimed design.
